[57] CLAIM

The ornamental design for a culinary combination spoon, as shown and described.

DESCRIPTION

FIG. 1 is a perspective view of a culinary combination spoon showing my new design;

FIG. 2 is an elevational view taken from one end thereof;

FIG. 3 is an elevational view taken from the other end thereof;

FIG. 4 is a top plan view thereof;

FIG. 5 is a side elevational view thereof;

FIG. 6 is a bottom plan view thereof;

FIG. 7 is a perspective view of a modification of my culinary combination spoon;

FIG. 8 is an elevational view taken from one end thereof;

FIG. 9 is an elevational view taken from the other end thereof;

FIG. 10 is a top plan view thereof;

FIG. 11 is a side elevational view thereof; and

FIG. 12 is a bottom plan view thereof.
